[57] CLAIM

The ornamental design for a mailbox support and post, showing my new design.

DESCRIPTION

FIG. 1 is a perspective view, right frontal, of a mailbox support and post showing my new design;

FIG. 2 is a top plan view thereof;

FIG. 3 is a side elevational view thereof, the other side being the same;

FIG. 4 is a front elevational view thereof;

FIG. 5 is a rear elevational view thereof; and,

FIG. 6 is a bottom plan view thereof.
